FRANS T. STRÖBECK, OF BEACHMONT, MASSACHUSETTS, ASSIGNOR TO THE SINGER
MANUFACTURING COMPANY, A CORPORATION OF NEW JERSEY.

MACHINE FOR STITCHING TAPE TO INNERSOLES.

1,265,399.

Specification of Letters Patent.

Patented May 7, 1918.

Application filed June 29, 1916. Serial No. 106,553.

To all whom it may concern:

Be it known that I, FRANS T. STRÖBECK, a citizen of the United States, residing at Beachmont, in the county of Suffolk and State of Massachusetts, have invented certain new and useful Improvements in Machines for Stitching Tape to Innersoles, of which the following is a specification, reference being had therein to the accompanying drawings.

This invention relates to sewing machines, more particularly of the flat-bed type, and has for an object the construction of a machine specially fitted for attaching a strip of tape to the reduced or feathered edge of an innersole to form a stitch-receiving rib for the inseam stitches common to welted shoes.

The innersole, the production of which is facilitated by the present improvement, consists of a shaped piece of sheet-material such as fiber-board of which the marginal portion is reduced in thickness to form a feather. Secured to the base of the feather, close to the shoulder formed at the juncture of the feather with the body portion of the innersole, is a longitudinally folded strip of tape, preferably of rubber-coated canvas material, the securing means consisting of a line of stitches passing substantially through the longitudinal center line of the tape. An additional layer of canvas, folded marginally to accommodate the up-standing edges of the tape, is cemented to the inner-sole and forms, together with the folded tape, a reinforced lip adapted to receive the well-known inseam stitches. Inasmuch as the stitches which hold the tape in place are set below the surface of the innersole, there is no danger of their being broken or punctured by the awl and needle of the welting machine.

In stitching the tape to an innersole, as above described, it is desirable that the tape be folded into trough-like form, prior to its presentation to the needle, so that the stitches may draw the tape snugly into the grooved or reduced portion of the innersole. It is also desirable that the tape be free from the retarding and flattening action of pressure exerting surfaces, common to strip guides of the prior art, which would seriously in-

terfere with the feeding of the tape, particularly if rubber coated, and would render it exceedingly difficult to stitch the tape to position while rounding the toe.

The present improvement, in its preferred embodiment, makes use of a lock-stitch machine having a frame including a bed-plate and the usual overhanging bracket-arm and head in which is journaled a reciprocating needle-bar carrying a straight needle and the usual spring-pressed presser-bar carrying a roller-presser disposed at the side of the needle and coöperating as usual with a feed-dog. In combination with the above instrumentalities, I employ tape and work-guiding means especially constructed and arranged to assist in properly positioning the tape and innersole relatively to each other and to the stitching point.

The tape-guiding means preferably consists of a folder-guide which is formed with a short guiding channel of U-shaped cross-section, inclined downwardly toward the stitching point. The delivering end of the guiding channel is disposed close to and directly in front of the needle-path and is so arranged that the needle will stitch preferably through substantially the center line of tape. A guide preferably in the form of a fin is, in the present instance, rigidly secured to the lower convex side of the folder-guide and projects downwardly a short distance to form an edge-guide for the innersole. The folder-guide may conveniently be sustained by a laterally bowed shank adjustably secured to the head of the machine. An auxiliary guide is preferably provided for keeping the tape from coming in contact with the roller-presser in its passage to the folder-guide.

A fuller understanding of the invention may be had from the detailed description and the accompanying drawings in which Figure 1 is a front elevation of the folder-guide and the instrumentalities coöperating therewith. Fig. 2 is a side elevation of the same. Fig. 3 is a rear elevation. Fig. 4 is a plan view. Fig. 5 is a sectional view of the complete innersole, the production of which the present improvement is constructed to facilitate.

In the present instance, I preferably

utilize a machine having a frame comprising a flat-bed 1 and throat-plate 2 above which is positioned the usual overhanging head 3 in which is journaled the needle-bar 4 carrying the eye-pointed needle 5 which co-operates with the usual loop-taker to form stitches. The presser-bar 6, mounted in the head 3 and pressed downwardly by the usual spring (not shown), 10 carries at its lower end a bracket 7 formed with laterally projecting spaced ears 8, 8, in which are threaded opposed pointed screws 9, 9, which enter corresponding depressions at the upper end of a downwardly 15 and forwardly extending bar 10 carrying at its free end a screw-pin 11 on which the presser-wheel 12 is journaled in opposed relation to a feed-dog 13 which rises through a slot in the throat-plate at one 20 side of the needle-hole 14. The spring 7 mounted on the bracket 7 acts to yieldingly maintain the adjustable stop-screw 10", which is carried by the bar 10, in contact with the shoulder 7". The bar 10 may, 25 when desired, be turned about the pivot screw 9 to displace the presser-wheel from operative position.

The folder-guide 15 is preferably carried at the lower free end of a laterally bowed shank 16 whose upper end is provided with vertically elongated slots 17, 17, entered by screws 18, 18 which are threaded into the lower end-portion of the head 3. The face-plate 3' is cut away, as shown in Fig. 1, 30 to accommodate the shank 16 and screw 18, 18. The body of the folder-guide 15 is, in the present embodiment of the invention, constructed from a piece of sheet-metal bent to U-form and having the upper edge- 35 portions 19 turned inwardly and downwardly, into substantial parallelism with their outer side walls, respectively, thus forming a short guiding channel which is U-shaped in cross-section. The guide 15 is 40 preferably inclined downwardly toward the stitching point and its delivering end is preferably disposed directly in front of the needle path so that the needle will stitch through substantially the center line of the 45 tape, as best shown in Figs. 2 and 4.

It is usually desirable to provide a guide for the innersole so that the stitches may be accurately placed as desired in the grooved or reduced portion adjacent the 50 edge of the innersole. For this purpose I prefer to employ a triangle-shaped, vertically disposed fin 20, which is rigidly secured to the lower convex side of the folder-guide and projects downwardly a 55 short distance terminating in a blunt horizontal edge 21 which is spaced from the throat-plate a distance equal to, or slightly greater than, the thickness of the feather. This spacing of the guide-fin above the 60 throat-plate may be varied by adjusting the

shank 16 vertically. The guide-fin 20 has the active work-guiding surface 20', Fig. 1, which extends downwardly away from the lower curved portion of the folder-guide 15, in a direction substantially normal thereto, and serves in the present instance to position the shoulder of the innersole so that the needle 5 will just miss it. The guide-fin also acts as a stripper, to assist the presser-wheel in stripping the innersole 75 from the rising needle, and forms an abutment against which the usual take-up (not shown) may set the stitches.

An auxiliary tape-guide, having the form of a bent arm 22, secured by screws to the face-plate 3' and constructed with a guiding slot 23, is preferably provided to lead the tape from the source of supply to the folder-guide and keep the tape from coming in contact with the presser-wheel. For this 85 latter purpose the auxiliary guide is disposed above and at the side of the folder-guide remote from the presser-wheel, as shown in Fig. 1.

In the operation of the device an inner-sole having the body portion *a* and the reduced or feathered portion *b* is placed on the throat-plate with the shoulder *c* against the active surface 20' of the guide-fin 20, after which the presser-wheel 12 is lowered 95 and acts to yieldingly hold the body portion *a* in position to be engaged and fed by the feed-dog 13. The tape *d*, folded into U-form by the folder-guide 15, is presented to the needle 5 which stitches through the center line of the tape and the portion *b* of the innersole which is reduced in thickness, thus sharpening the line of fold and drawing it snugly against said reduced portion *a*, and, in the embodiment shown in Figs. 100 2 and 4, into the angle at the base of the feather. This action results in setting the 105 stitches *e* below the surface of the body portion *a*.

It will be noted that I have avoided the 110 use of pressure-exerting surfaces which in prior tape-guide constructions have commonly been brought to bear upon the stitched tape. Such surfaces in the present instance would greatly impede the feeding 115 of the work if a rubber coated tape were used and would flatten the tape, rendering it difficult to stitch the tape around the sharp curve at the toe of the innersole, where the two upstanding halves of the 120 tape-strip have a strong tendency to be drawn into intimate contact with each other, due to the fact that the tape is folded longitudinally and is then curved about the toe.

While I have shown and described what I consider to be the preferred embodiment of the invention, it is to be understood that various changes in the form and arrangement of the co-operating parts and support- 125 130

ing means therefor may be made without departure from the spirit of the invention.

Having thus set forth the nature of the invention, what I claim herein is:—

- 6 1. In a sewing machine, in combination, stitch-forming mechanism including a reciprocating straight needle, a work-support, a folder-guide comprising a body portion, having a tape-guiding channel whose delivering end is substantially U-shaped in cross-section, said folder-guide being so disposed adjacent the needle-path as to present the tape to the needle in the form of an upwardly opening trough, whereby the needle 10 may descend into the trough.
- 10 2. In a sewing machine, in combination, stitch-forming mechanism including a reciprocating straight needle, a substantially flat work-supporting plate, feeding mechanism 20 including a feed-dog adapted to engage the work through an aperture in said work-supporting plate, and tape-guiding means disposed above said plate and including guiding surfaces constructed and arranged to 25 present a strip of tape to the needle in the form of an upwardly opening trough, said needle being adapted to enter the trough.
- 30 3. In a sewing machine, in combination, stitch-forming mechanism including a reciprocating needle, a work-support, a feeding implement, a presser-member opposed to said feeding implement and acting at one side of the line of stitching, and a tape-guide having a U-shaped channel adapted to deliver tape to the needle in trough-like form at one side of said presser-member, whereby the stitched tape is free from the action of pressure exerting surfaces.
- 35 4. In a sewing machine, in combination, stitch-forming mechanism including a reciprocating needle, a work-support, a feeding implement, a presser-member opposed to said feeding implement and acting at one side of the line of stitching, a tape-guide 45 having a channel adapted to deliver tape to the needle at one side of said presser member, whereby the stitched tape is free from the action of the pressure exerting surfaces, and work-guiding means disposed between 50 said tape-guiding channel and said work-support.
5. In a sewing machine, in combination, stitch-forming mechanism including a reciprocating needle, a work-support, a folder-guide, comprising a body portion, having a tape-guiding channel whose delivering end is substantially U-shaped in cross-section, said delivering end being so disposed adjacent the needle path that the stitches are received in the fold of the strip of tape as it 60 issues from said folder-guide, and work-

guiding means disposed between said body portion and said work-support.

6. In a sewing machine, in combination, stitch-forming mechanism including a reciprocating needle, a work-support, a folder-guide comprising a body portion, having a tape-guiding channel whose delivering end is substantially U-shaped in cross-section, said delivering end being so disposed adjacent the needle path that the stitches are received in the fold of the strip of tape as it issues from said folder-guide, and work-guiding means carried by said tape-guide and disposed between said body portion and said work-support.

7. A combined tape and work-guide for sewing machines comprising, in combination, a member having a tape-guiding channel whose delivering end is substantially U-shaped in cross-section and a work-guiding portion, said work-guiding portion having a work-guiding surface disposed adjacent the delivering end of said channel and extending away from the curved portion of said channel.

8. In a sewing machine, in combination, stitch-forming mechanism including a reciprocating needle, a feeding implement, a work-plate, a tape-guide adjustably fixed in a position spaced from the surface of said work-plate and having a substantially U-shaped tape-guiding channel arranged to deliver tape to the stitching point, and a presser member having a pressure exerting surface, disposed wholly at the side of the stitching line and opposed to said feeding implement.

9. In a sewing machine, in combination, a frame including a flat-bed plate and an overhanging bracket-arm, stitch-forming mechanism including a reciprocating needle journaled in the free end of said bracket-arm, a guide-member rigidly sustained by said bracket-arm and provided with a tape-guiding channel of U-shaped cross-section whose delivering end is disposed directly in front of the needle-path, said U-shaped channel being convexed toward the bed-plate, a roller-presser disposed wholly at one side of said guide-member and the stitching line, and an auxiliary tape-guide disposed on the opposite side of the stitching line and above the first-mentioned guide-member.

In testimony whereof I have signed my name to this specification.
